UNITED STATES PATENT OFFICE.

WILLIAM C. CAMPBELL, OF SEATTLE, WASHINGTON, ASSIGNOR TO FRANK KOPEJTKO,
OF ST. LOUIS, MISSOURI.

WASHABLE INSOLE FOR SHOES.

Application filed July 3, 1925. Serial No. 41,331.

This invention relates to shoe insoles, and has for its main object to provide an inexpensive insole that will effectively absorb perspiration; that will tend to keep the user's feet warm in cold weather and cool in hot weather, and which can be washed so as to keep it in a sanitary condition.

Another object is to provide a shoe insole of the character above described that is sufficiently soft and flexible to be perfectly comfortable to the user and which is of such construction that it will not creep upwardly behind the user's heel. Other objects and desirable features of my invention will be 15 hereinafter pointed out.

Figure 1 of the drawings is a top plan view of a shoe insole constructed in accordance with my invention.

Figure 2 is a bottom plan view of said 20 insole.

Figure 3 is a longitudinal sectional view, taken on the line 3—3 of Figure 1.

Figure 4 is a transverse sectional view, taken on the line 4—4 of Figure 2; and

25 Figure 5 is a bottom plan view, illustrating a slight modification of my invention.

In the drawings A designates a member that is shaped to fit inside of a shoe flat against the sole of the shoe so as to serve 30 as an insole. Said member is constructed of matting or any other suitable woven straw material that can be washed or scrubbed without liability of injuring the same, and it is preferably provided with a binding 1 of tape or the like which embraces the peripheral edge portion of said member and is secured to same by stitches 2. In most instances the bottom side of the member A will be protected by a facing 3 of thin cloth that is secured to said member by 35 stitches 4, herein illustrated as extending transversely of said member.

When the member A is arranged in operative position inside of a shoe the top side of 40 same will contact directly with the user's sock or stocking, and accordingly, will effectively absorb perspiration from the user's foot. Due to the fact that it is constructed from straw material, the member A can be 45 washed or scrubbed without liability of injuring the same, and moreover, it is an effective insulator, both for heat and cold, and thus tends to keep the user's feet warm in cold weather and cool in hot weather. In 50 addition to affording great comfort and pro-

tection to the user's feet, my improved insole keeps the user's shoes in a sanitary condition and prevents the soles of same from being soiled and made hard and brittle by perspiration from the user's feet. 60

In order to eliminate the possibility of the member A creeping upwardly back of the user's heel, I provide the underside of said member with a pocket 5 of thin cloth in which a heel piece 6 of leather or cardboard can be arranged so as to impart sufficient stiffness to the heel portion of the member A to retain it in operative position in the user's shoe. When it becomes necessary or desirable to wash the insole the 70 stiffening element 6 is withdrawn from the pocket 5, and after said insole has been washed and dried, said stiffening element is re-inserted in said pocket preparatory to arranging the insole in operative position inside of the user's shoe. In instances where the user naturally assumes such a position in standing or walking that his weight is distributed unevenly on the heels of his shoes, thus tending to cause the heels to wear 75 unevenly or "run over", the insert or stiffening element 6 that is combined with the heel end portion of the member A may be tapered slightly in transverse cross section, as shown in Figure 4. Likewise, if it is desired to 80 slightly raise the heel of the user's foot, a longitudinally-tapered insert or stiffening element 6 can be arranged in the pocket 5 of the member A, as shown in Figure 3.

In most instances it is only necessary or 90 desirable to stiffen the heel end portion of the member A, but in case it is desired to stiffen the portion of said member which extends under the ball of the user's foot, the member A can be provided on its underside 95 with a double pocket 5^a, as shown in Figure 5, that is adapted to receive two stiffening elements 6^a and 6^b for the front and rear end portions of the insole.

A shoe insole of the construction above 100 described is inexpensive to manufacture; it materially prolongs the life of the user's shoe by absorbing the perspiration from the user's foot; it can be kept in a sanitary condition, as it is not injuriously affected by 105 washing or scrubbing; it tends to keep the user's feet cool in warm weather and warm in cold weather, and notwithstanding the fact that it is pliable and perfectly comfortable, the stiffening element that is com- 110

combined with the heel portion of same effectively prevents it from creeping up behind the user's heel.

Having thus described my invention, what I claim as new and desire to secure by Letters Patent is:

1. A washable shoe insole consisting of a member constructed from a piece of woven straw material that is shaped to fit inside of a shoe against the sole of the shoe, a pocket on the underside of said member that is adapted to receive a heel stiffening element, and a binding secured to the edge portion of said member.
- 10 2. A washable shoe insole consisting of a member constructed from a piece of woven straw material that is shaped to fit inside of a shoe against the sole of the shoe, a binding that embraces the edge portion of said

member, a cloth facing that covers the underside of said member, and a pocket on the underside of said member that is adapted to receive a removable heel stiffening element.

3. A washable shoe insole consisting of a member constructed from a piece of straw matting shaped to fit inside of a shoe against the sole of the shoe, a binding of tape embracing the edge portion of said member and secured to the same by stitches, a cloth facing covering the underside of said member and secured to the same by stitches, a cloth pocket on the underside of said member arranged adjacent the rear end of the same, and a stiffening element removably mounted in said pocket and arranged under the heel end portion of said member.

WILLIAM C. CAMPBELL.
